ALICE VIOLET BENNETT, OF LONDON, ENGLAND

KEYBOARD OPERATED MUSICAL INSTRUMENT

Application filed December 11, 1929, Serial No. 413,301, and in Great Britain December 14, 1928.

This invention relates to musical instruments in which the sound to be produced is obtained by actuating the keys of a keyboard after the manner of playing a piano, and in which the keys bring hammers or strikers into contact with suitable sound producing members.

The object of my invention is to provide a simple and efficient type of instrument by means of which a high tonal quality or timbre is produced from a set of sonorous bodies. A further object of my invention is to provide a novel construction and arrangement of sonorous bodies particularly suitable for generating a harmonious scale or scales of ringing or bell-like sounds.

Broadly my invention consists in a series of sonorous bodies in juxtaposition to a series of strikers or hammers each connected to its appropriate one of a number of keys arranged substantially after the manner of a piano keyboard, the sonorous bodies each being in the form of a length of metal secured at one end and free to vibrate about each secured end.

The sonorous bodies can be a series of metal rods secured to a horizontal bar and progressively increasing in length from one end to the other in order to obtain the desired scale. Alternatively each sonorous body may be in the form of a convolute length of metal, for instance a length of steel spring wound to the desired convolutions after the manner of some clock springs. The inner ends of the convolute members are fixed to the horizontal bar. The said horizontal bar preferably extends completely along the interior of a box-like compartment which may have a sound board across its rear wall.

Any suitable number of sets of sonorous bodies can be provided supported in the manner above described, and strikers or hammers corresponding in number to the said sonorous bodies are provided beneath the sonorous bodies. It is preferred to employ hammers faced with felt, leather or other suitable material, each hammer consisting of a link pivoted at one end to a suitable horizontal frame member and formed at its other and free end with an upwardly projecting striker. The said frame member can comprise a wooden

bar secured at its ends to the end walls of the box-like sound compartment and having one or a large number of slots formed in it to receive short strips of vellum or other suitable flexible material pivotally connecting the said links to the said wooden bar. Actually it is preferred to provide the said slots by locating the pieces of vellum or their equivalent between the said wooden bar and a detachable strip of wood or other suitable material.

Normally the links of the hammers incline downwards towards their free ends which are preferably their front ends, and are supported on upstanding strikers or forks formed on the inner ends of the keys which can be fulcrumed in well known manner, consequently when a key is struck the corresponding hammer will be struck upwards and will strike and rebound off the appropriate sonorous body, the hammer returning to its normal position by reason of its own weight.

A damper action may be provided by mounting on the inner end of each key an upstanding rod having a curved upper end normally residing against the upper side of the appropriate sonorous body, but raised therefrom immediately upon the depression of a key by the person playing the instrument. As soon as a key is released its damper will engage the appropriate sonorous body and arrest its vibration.

In order that my invention may be clearly understood and readily carried into effect I have appended hereto a sheet of drawings illustrating embodiments of my invention, and wherein:—

Fig. 1 is a sectional side elevation of the preferred form of my invention.

Fig. 2 is a detail plan view showing the arrangement of keys and hammers.

Fig. 3 is a detail diagrammatic view showing a method of arranging an appropriate scale of notes.

Fig. 4 is a sectional side elevation view showing a modified form of sonorous bodies and arrangement of striker mechanism.

Referring to the drawings the instrument is shown with an arrangement of keys 1 of any suitable number of octaves similar to the keys of a piano, and a corresponding

number of sonorous bodies 2, which in Figs. 1, 2 and 3 are shown as a series of round section, or other suitable section, solid or hollow straight rods secured at one end to to 5 a horizontal metal or other suitable bar 3 extending across the end walls 4 of a box-like sound compartment 5. The keys 1 can pivot on a common horizontal bar 6 secured to a base board 7 in proximity to the 10 plane of the front wall 8 of the compartment 5, suitable dowels 9 secured to the bar 6 locating the keys in their proper positions and permitting them to fulcrum on the bar 6 by reason of slots 10 in the keys receiving the 15 dowels 9. Suitable strips of material, for instance felt, 11, provide a quiet and easy movement of the keys 1, and the actuated ends of the keys are recessed underneath to receive guide pins 12 secured to and upstanding from the base 7, felt, rubber or other suitable strips 13 providing buffers for the keys 1 when they are depressed.

The sonorous members 2 are adapted to be struck by hammers in the form of links 14 25 having suitable weighted striking heads 15 upstanding therefrom the free ends of the heads 15 preferably being covered with felt, leather or other suitable members 16 for engaging the sonorous members 2.

30 The hammers are pivotally connected to a common horizontal bar 17 preferably by means of short flexible connecting strips 18, for instance pieces of vellum, each secured in a slit in one end of a link 14, or otherwise 35 suitably connected thereto, and clamped between the bar 17 and a detachable securing strip 19. Instead of a single strip 19, a short plate may be provided for each hammer, whereby the hammers may be individually removed when necessary.

40 Normally the free ends of the links 14 rest upon the keys 1, each of which preferably has a felt, rubber or other suitable pad 20 secured to its upper surface to absorb the 45 noise and shock of the falling hammers. The hammers are struck smartly upwards upon the depression of the keys, each key having at its inner end a striker 21 for this purpose, the strikers 21 preferably being arranged 50 at right angles to the normal inclination of the hammers 14 as shown in Fig. 1 so that there is obtained a clean striking action of the strikers 21 against the hammers, instead of a glancing striking action. The 55 heads of the strikers 21 are fitted with felt, or other suitable noise absorbing caps 22 which normally lightly contact with the links 14. The strikers 21 preferably have their heads threaded on to pins 23 secured in the 60 keys 1 whereby they may be adjusted as regards their extension from the keys.

The rear ends of the keys normally rest by reason of their predominance of weight over their front ends, upon a felt or other 65 suitable shock and sound absorbing strip 24

secured on a bar 25 fixed to the base 7, the rear ends of the keys if necessary being loaded with metal, for instance by boring the rear end of each key to receive a metal body 26.

70 It is preferred that each sonorous member 2 shall have its anchored end tapered or restricted in diameter at its junction to the bar 3 to ensure a ready vibration as indicated at 2a in Fig. 1, this end of each rod 2 preferably being threaded into a securing screw 27 as shown, each hole in the bar 3 which receives a rod 2 preferably being flared at its inner end, as indicated at 28, to permit a freedom of vibration of the rods 2.

75 Depression of a key 1 will cause the appropriate hammer to fly upwards against the appropriate rod 2 relative to the striker 21, the arc of movement of the hammers being greater than that of the strikers 21 so as to avoid any damper action if a key is maintained depressed.

80 If it is desired to make the instrument portable, the key base 7 can, as shown in Fig. 1, be adapted to be slid relative to the compartment 5 to an extent which will enable the base 7 to be accommodated completely within the compartment 5, the ends of the base 7 and the end walls 4 having inter-engaging projections and grooves to guide the base 7. The front end of the keyboard can be covered by a board 29, hinged to the front edge of the base 30 of the compartment 5 as indicated at 31 so that when the instrument is in use it can lie horizontally, but when the keyboard is slid into the compartment 5, the hinged board 29 can be folded against the front wall 8 of the compartment 5, with its front shield 29a closing a correspondingly dimensioned opening 32 in the top 33 of the compartment 5. A music rest can be folded 90 into the compartment 5 and a lock or other suitable securing device 35 can engage with a co-operating member on the shield 29a. The hinged board 29 can have a carrying 95 handle.

100 The position of the slideable board and keys within the compartment 5 when folded away is preferably such that all or the majority of the hammers will not strike the sonorous rods 2, whereby any shaking of the instrument will not produce any, or many, musical sounds.

110 Instead of having straight sonorous rods 2 as shown in Fig. 1, a series of convolute lengths of metal rod 2b may be employed as 115 shown in Fig. 4, the convolute rods being secured at their inner ends to a common bar 3a corresponding to the bar 3. The arrangement of strikers may be as shown in Fig. 1. However, I have shown a modified striker 120 mechanism in which hammers 36 with heads 37 similar to the hammer heads employed in pianos are pivoted in slots in a bar 17a secured across the end walls 4 of the compartment 5 or to the front wall 8. The hammers 125

36 normally rest in the forked upper ends of a series of strikers 21a in the form rods secured to the keys 1. The strikers are inclined relative to the keys 1 so that they normally lie substantially at right angles to the downwardly inclined hammers in the same manner as shown in Fig. 1, the hammers and strikers however in this instance being arranged with their free ends directed rearwards of the instrument instead of forwards.

If desired a damper device may be provided for the sonorous bodies 2 or 2b for instance as shown in Fig. 4 in which each key 1 has attached to its rear end an upstanding arm 38 bent at its upper end so as to normally lie against a sonorous member 2 or 2b, and preferably formed with a felt or other suitable head 39 to engage the appropriate sonorous member. It will be apparent that as each key is depressed to play a note the damper member of the selected key will move clear of the appropriate sonorous member in advance of the striking thereof, and upon releasing the key the damper will engage and damp the sonorous member.

The striker mechanism shown in Fig. 4 can be adapted to be slid into the compartment 5 in the same manner as that shown in Fig. 1.

By means of my invention a very simple but very attractive musical instrument is provided which will be useful as an inexpensive substitute for a piano and will introduce a novel and fascinating tone in orchestral work.

35 Although a portable type of piano is illustrated it is to be understood that my invention may be applied to a full size standard type of upright or grand piano.

I claim:

40 1. A keyboard operated musical instrument comprising a support, a series of sonorous bodies secured to said support, a second support, a series of hammers carried by said second support, one in juxtaposition to each of said bodies, and a series of keys adapted to operate said hammers to strike said bodies, said supports being relatively movable so that said bodies are movable out of the path of operation of said hammers.

45 2. A keyboard operated musical instrument comprising a box-like container, a series of sonorous bodies mounted within said container, a support slidably mounted within said container, a series of hammers carried by said support, a series of keys comprising a keyboard also carried by said support and adapted to operate said hammers, the arrangement being such that said support may be moved into a position in which the keyboard is located outside said container and in which the hammers when operated will strike said bodies and may also be moved into a position in which the keyboard is located

50 within said container and said hammers operate in a portion of the container not occupied by said bodies.

3. A keyboard operated musical instrument comprising a comparatively long but shallow box-like container, a series of sonorous bodies mounted within said container and extending only partially therethrough, a support mounted within said container, a series of hammers carried by said support, and a series of keys also carried by said support and adapted to operate said hammers, said support being slidable in the direction of the length of said container so that in one position the keyboard is located outside said container and the hammers will strike said bodies when operated, and so that in another position the keyboard is within said container and the keys are located in that part of said container not occupied by said bodies.

4. A keyboard operated musical instrument comprising a comparatively long but shallow box-like container, a series of sonorous bodies mounted within said container and extending only partially therethrough, a support mounted within said container, a series of hammers carried by said support and a series of keys also carried by said support, adapted to operate said hammers, said support being slidable in the direction of the length of said container so that in one position the keyboard is located outside said container and the hammers will strike said bodies when operated, and so that in another position the keyboard is within said container, and the keys are located in that part of said container not occupied by said bodies, and a board hinged to the front of said container and adapted to form the front vertical wall thereof when the keyboard is within the container, said board lying in a horizontal plane beneath said keyboard when the latter is outside said container.

5. A keyboard operated musical instrument comprising a comparatively long but shallow box-like container, a support located along the front of said container, a series of sonorous bodies in the form of straight rods each secured at one end to said support and extending within said container in the direction of the length thereof and free at their other ends, a second support, a series of hammers carried by said second support, one in juxtaposition to each of said bodies, and a series of keys adapted to operate said hammers to strike said bodies, said supports being relatively movable so that said bodies are out of the path of operation of said hammers.

6. A keyboard operated musical instrument comprising a box-like container, a member secured along the front of said container, a series of sonorous bodies in the form of straight rods each secured at one end to said member and extending within said container in the direction of the length thereof and free at their other ends, a support slidably

mounted within said container, a series of hammers carried by said support, a series of keys comprising a keyboard also carried by said support and adapted to operate said hammers, the arrangement being such that said support may be moved into a position in which the hammers when operated will strike said bodies and may also be moved into a position in which the hammers operate in a portion of the container not occupied by said bodies.

7. A keyboard operated musical instrument comprising a comparatively long but shallow box-like container, a supporting member located along the front of said container, a series of sonorous bodies in the form of straight rods each secured at one end to said member extending within said container and partially therethrough in the direction of the length thereof and free at their other ends, a support mounted within said container, a series of hammers carried by said support, a series of keys also carried by said support and adapted to operate said hammers, said support being slidable in the direction of the length of said container so that in one position the keyboard is located outside said container and the hammers will strike said bodies when operated, and so that in another position the keyboard is within said container, and the keys are located in that part of said container not occupied by said bodies.

8. A keyboard operated musical instrument comprising a box-like container, a supporting rod mounted within said container, a series of convolute rods secured at their inner ends to said supporting rod and free at their outer ends, a series of hammers mounted within said container below said convolute rods, a series of keys adapted to operate said hammers, and a series of dampers one secured directly on each of said keys and normally in contact with the upper side of said convolute rods.
